ABSTRACT: An insulator top clamp for connecting a cable to the top of an insulator having a cable-receiving channel with a lip at one end with means for attaching the clamp to the insulator for pivotal movement at that end and a jaw member at the remaining end for connecting the cable to the clamp.

INSULATOR TOP CLAMP

BACKGROUND OF THE INVENTION

In electrical powerline work, it frequently becomes necessary to connect a cable to a vertically projecting insulator on the top of the type found on crossarms of a pole. For this purpose, insulator top clamps are utilized and these clamps in order to be useful must be easy to manipulate and provide ease with which to insert the cable and fasten the same to the clamp. Additionally, it is necessary that there be room for marginal relative movement of the various parts so that high accuracy is not required. Provision must also be made that the connection can be made by means of a bolt of the type having a hex head or by means of an eyebolt depending upon the desires of the lineman. The construction must be simple and rugged.

SUMMARY OF THE INVENTION

An insulating top clamp including, in combination, an elongated body having a "U"-shaped channel formed therein throughout its length, first and second lips formed on the ends of the channels, each of the lips providing a depressed base with a widened sidewall, means for attaching the clamp to an insulator with the channel facing upwardly at one end of the clamp with the connection allowing pivotal movement of the clamp in a vertical plane, and means for providing easy fastening of the cable to the clamp.

DESCRIPTION OF THE DRAWINGS

In the accompanying drawings,

FIG. 1 is an exploded perspective view of an insulator top clamp constructed in accordance with this invention;

FIG. 2 is a longitudinal view of the clamp shown in FIG. 1 in assembled condition with a cable maintained therein;

FIG. 3 is a top view of the clamp shown in FIG. 2; and

FIG. 4 is a partially sectional view taken along the line 4—5 in the direction of the arrows in FIG. 3.

DESCRIPTION OF THE PREFERRED EMBODIMENT

The insulator top clamp of the present invention consists of an elongated body 10 which is formed with an upwardly facing "U"-channel 12 which terminates at either end in a lip providing a depressed base of the "U"-channel and channel sidewalls of increased or widened spacing. Hence, in the figure, lip 14 having a depressed base of the channel 14a and sidewalls 14b is formed at one end of the body while lip 16 having a base 16a and sidewalls 16b is formed at the remaining end of the body. The lip 14 occupies a greater portion of the body than lip 16. For instance, the depressed base 14a is inclined and greater in length than the depressed base 16a. In each instance, the walls are formed to begin to provide the increased spacing in a gradual manner at the point whereat the base begins its incline. Turret members 18 and 20 project transversely from

body 10. The turret members project from walls 14b of lip 14. Each of the turrets is cylindrical in form with a concentric slot providing a female connection for joining with a complementary male projection formed on an insulator (not shown) to provide a pivotal connection for movement in a vertical plane. Hence, turret 18 is provided with female slot 18a and turret 20 is provided with female slot 20a. It is noted that the axis of the turrets forms the pivotal axis for movement in the vertical plane and that this axis passes substantially through a cable 22 disposed within channel 12.

A vertical guide channel 24 is provided within which jaw member 26 can move upon rotation of hex head bolt 28 which passes through opening 30 in the base of channel 24 to engage threaded insert 32 of the jaw member. The jaw member 32 overlies a portion of channel 12 adjacent lip 16, and the means for moving the jaw member toward and away from the body which includes the bolt means 28 is disposed to one side of the channel so that there is unobstructed access to the channel from the side thereof indicated by the numeral 34. Grommet 35 is provided to hold the male member 26 up out of the way while installing conductor 22. In the absence of the grommet, in the position normally used, gravity would hold this male member in the closed position, unless held up either by hand or a hot stick off the socket wrench, with which the lineman is manipulating the clamp, any of which would be awkward.

With this arrangement, the lineman has at all times unobstructed access to the channel without disassembly of any parts other than the loosening of bolt 28, and in view of the allowance of movement in a vertical plane about the turrets, the positioning is not critical. Additionally, the hex head bolt can be replaced by an eyebolt wherever it is desired. Also, in the preferred form of the embodiment, the end of bolt 28 is peened after assembly so that the lineman in manipulating the assembly will not be able to inadvertently separate the jaw member from bolt 28.

I claim:

1. An insulator top clamp including, in combination, an elongated body having a "U"-channel formed therein throughout its length, first and second ends of said "U"-channel, first and second lips respectively formed on said first and second ends, each of said lips providing a depressed base of said channel with widened sidewalls, said first lip occupying a greater portion of said body than said second lip, transverse turrets projecting from said body at said first lip, said turrets having cylindrical surfaces formed to cooperate with complementary surfaces of said insulator allowing pivotal movement of said body in a vertical plane with said channel facing upwardly, a cooperating jaw member overlying a portion of said channel, and means for moving said jaw member toward and away from said body, same means allowing unobstructed access to said channel from the side thereof.

2. An insulator top clamp in accordance with claim 1 in which said jaw member is adjacent said second lip.
